WHEEL DRESSING DEVICE

La Vern M. Bargren, Rockford, Ill., assignor to
 Barber-Colman Company, Rockford, Ill., a corporation of Illinois

Application July 28, 1948, Serial No. 41,151

4 Claims. (Cl. 125—11)

1

This invention relates to a device for supporting a dressing tool for movement back and forth across the face of a grinding wheel to dress the face to a desired contour.

The primary object is to provide a dressing device in which the tool is movable through a fixed range which is bodily shiftable in the direction of the dressing motion so as to compensate for wearing off of the wheel face.

The invention also resides in the novel and simple character of the construction which contributes to overall compactness and facilitates adjustment to adapt the device to the changing size of the grinding wheel.

Other objects and advantages of the invention will become apparent from the following detailed description taken in connection with the accompanying drawings, in which:

Figure 1 is a fragmentary side view of a grinding machine equipped with the improved dressing device which is shown in vertical section.

Fig. 2 is a fragmentary section taken along the line 2—2 of Fig. 1.

Fig. 3 is a fragmentary section taken along the line 3—3 of Fig. 2.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

In the form shown in the drawings for purposes of illustration, the improved dressing device is built into a grinding machine and adapted to dress the frustoconical peripheral face 10 of a wheel 11 fixed to a rotary spindle 12 which is journaled in an axially adjustable sleeve 13. Such adjustment is effected through a worm and wheel 14 and a rack and pinion 15 in response to manual turning of a knob 16. By such adjustment, the active surface of the wheel may be maintained in proper position relative to the work as the wheel wears down to the size shown in phantom in Fig. 1.

The dressing tool or diamond point 17 is clamped in the bar 18 by a clamping screw 19 which pulls the split end together. In the present instance, dressing of the wheel face is effected by a reciprocatory movement of the tool. For this purpose, the bar projects into and is slidably guided by a sleeve 20 which is in turn slidable

2

in a guide sleeve 21 mounted in the proper position in an extension 22 of the grinding machine frame. A longitudinally extending slot 23 is formed in the under side of the sleeve 21 to receive a stop 24 which cooperates with the ends of the slot to positively limit the range of reciprocation of the sleeve and, as will appear later, the range of movement of the tool 17. The stop projects into a groove 25 in the bar 18 and thus holds the latter against turning within the sleeve while permitting adjustment of the bar endwise relative to the sleeve. A flexible and extensible diaphragm 26 is stretched between flanges on the lower ends of the sleeves 20 and 21 and urges the former inwardly relative to the guide sleeve.

On the upper side, the guide sleeve 21 is slotted longitudinally to receive one side of a gear segment 26 fast on one end of a tubular rockshaft or tube 27 journaled in the bearing 28 on the frame extension 22. This shaft is keyed at 29 to a disk 30 with which a handle 31 is rigid and projects upwardly. A contractile spring 32 acts on an arm 33 on the sleeve 27 to urge the latter and the handle clockwise toward the normal retracted position shown in Fig. 1.

Extending through the tubular shaft and journaled in the latter and in a bearing 34 is a shaft 35 which is fixed to the hub of a gear segment 36 disposed adjacent the gear 26 and projecting through the slot in the guide sleeve and also through a slot in the sleeve 20. The teeth on the two segments 26 and 36 are of the same pitch and mesh respectively with rack teeth 37 and 38 formed on the sleeve 20 and on the rack bar 18.

Provision is made for normally locking the gears 26 and 36 together for turning in unison while permitting of disengagement of the coupling to allow for relative angular adjustment between the gears and, therefore, changing the retracted position of the dressing point 17. In the present instance, this coupling is of the yieldable type and formed by a detent 41 whose inner tapered end 46 is adapted to enter tapered notches between teeth 42 formed in the outer face of the disk 30 and angularly spaced and extending partly around the latter. The detent is slideable in a recess 44 in a disk or knob 47 pinned to the shaft 35 adjacent the disk 30. A compression spring 43 urges the detent into engagement with the teeth 42 with a force determined by the adjustment of a set screw 45.

With the end of the detent seated in one of the notches on the disk 30, the two disks and, therefore, the gears 26 and 36 will be coupled to-

gether and positively held in a predetermined angular relation so as to turn in unison as the handle 31 is swung back and forth to carry the dressing tool across the face of the grinding wheel. When it is desired to change the initial position of the dressing point to correspond to the changed diameter and axial position of the wheel face 10, the coupling may be disengaged and the tool supporting bar 18 advanced relative to the sleeve 20. This is accomplished by manually turning the knob 47 while the handle 31 is held against turning. When sufficient torque is thus applied to the knob, the detent will be cammed out of one of the notches and advanced to a succeeding notch, the bar 18 being advanced correspondingly. The extent of such relative adjustment between the bar 18 and the sleeve 20 may be sensed readily by the operator as the detent rides over the successive teeth 42. The range of such adjustment is limited by the length of an arcuate slot 49 in the disk 30 receiving a pin 50 which is fixed to the knob 47.

When the wheel 11 is new, and therefore of maximum diameter, the mechanism above described is adjusted to locate the dressing point in the position shown in full in Fig. 1, the handle 31 then being released. Such positioning is achieved by turning the knob 47 counterclockwise and slipping the detent clutch until the pin 50 comes against the end of the slot 49 as shown in Fig. 3. The dressing tool is then adjusted relative to the bar 18 to bring its point against a locating finger 51.

To dress the wheel face, the handle 31 is turned counterclockwise, thereby advancing the sleeve 20 and the bar 18 in unison until the end of the sleeve slot 23 encounters the stop 24. In this movement, the point 17 is passed across the wheel face 10 through a range *a* and to a position only slightly beyond the inner edge of the wheel face. As the handle is released, the tool is drawn back across the wheel face by the action of the spring 32.

As the wheel wears and is dressed down to a smaller diameter, it is retracted axially by adjustment of the knob 16. Then it becomes desirable to shift the range of reciprocation of the dressing tool so that the tool in its opposite limit positions is disposed close to but outwardly from the opposite margins of the wheel face 10. To effect this adjustment, the handle 31 is held in retracted position, and the knob 47 is manually turned clockwise to slip the detent coupling and advance the tool 17 to a position close to the outer end of the wheel face.

Such adjustment of the range of reciprocation of the dressing tool is effected intermittently throughout the life of the wheel until finally the wheel 10 will be sized and positioned as shown in phantom in Fig. 1. At this time, the knob 47 will have been turned throughout the length of the slot 49, and the mechanism will then be conditioned to reciprocate the tool through the range *b*. Then, when in its advanced position, the tool will be disposed as shown in phantom in Fig. 1.

By adjusting the range of reciprocation of the tool to correspond to the changing position of the wheel face, the dressing operations are greatly facilitated and the time consumed in dressing the wheel is minimized. This is because the tool engages the wheel face immediately in response to movement of the handle and substantially throughout the range of movement of the latter. For the same reason, the over-all dimensions of the dressing device as a whole are reduced to

4
a minimum. By making the coupling between the gears 26 and 36 disengageable in response to the transmission of a predetermined torque therethrough, the coupling also serves as a safety device to prevent damage to the wheel in the event that the latter is inadvertently adjusted to a position to interfere with the advance of the dressing tool.

I claim as my invention:

1. In a wheel dresser, the combination of, a sleeve mounted for endwise reciprocation through a fixed range, a rack bar slidable in and endwise of said sleeve with one end projecting from the sleeve and adapted for attachment of a dressing tool thereto, said sleeve being slotted longitudinally to expose the teeth of said rack bar and having rack teeth paralleling the bar teeth, first and second gears respectively meshing with teeth of said sleeve and bar, a second sleeve fixed to said first gear and urged in a direction to retract said bar, a handle fixed to said second sleeve, a shaft journaled in said second sleeve and fixed to said second gear, and a coupling having elements on said second sleeve and said shaft, one of said elements having angularly spaced tapered notches therein, and a detent on the other coupling element having a tapered end spring urged into one of said notches but retractable therefrom to permit of relative angular adjustment between said gears.

2. In a wheel dresser, the combination of, a sleeve mounted for endwise reciprocation through a fixed range, a rack bar slidable in and endwise of said sleeve with one end projecting from the sleeve and adapted for attachment of a dressing tool thereto, said sleeve being slotted longitudinally to expose the teeth of said rack and having rack teeth extending along the latter, first and second gears respectively meshing with the teeth of said sleeve and bar, a second sleeve fixed to said first gear and urged in a direction to retract said bar, a handle fixed to said second sleeve, a shaft journaled in said second sleeve and keyed to said second gear, and a coupling having elements on said second sleeve and said shaft normally engaged to hold said gears against turning relative to each other but disengageable to permit of relative angular adjustment of said gears.

3. In a wheel dresser, the combination of, a sleeve mounted for endwise reciprocation through a fixed range, a rack bar slidable in and endwise of said sleeve with one end projecting from the sleeve and adapted for attachment of a dressing tool thereto, said sleeve having rack teeth formed therealong and being slotted to expose the teeth of said rack, first and second gears respectively meshing with the teeth of said sleeve and bar, a handle rigid with said first gear, a coupling normally connecting said gears to turn in unison but adapted to permit relative angular adjustment between the two, and stop elements movable with the respective parts of said coupling and interengageable with each other to limit the range of such angular adjustment between said gears.

4. In a wheel dresser, the combination of, a sleeve mounted for endwise reciprocation through a fixed range, a rack bar slidable in and endwise of said sleeve with one end projecting from the sleeve and adapted for attachment of a dressing tool thereto, said sleeve having rack teeth formed therealong and being slotted to expose the teeth of said rack, first and second gears respectively meshing with the teeth

of said sleeve and bar, a handle rigid with said first gear, and coupling elements normally yieldably urged into interengagement to provide a drive connection between said gears, said elements being disengageable in response to a predetermined torque manually applied to one element whereby to permit of angular adjustment of said gears.
